UNITED STATES PATENT OFFICE.

GUS W. REYER, OF ROSE HILL, KANSAS.

PAD.

1,320,918.

Specification of Letters Patent.

Patented Nov. 4, 1919.

Application filed March 15, 1919. Serial No. 282,841.

To all whom it may concern:

Be it known that I, Gus W. REYER, a citizen of the United States, residing at Rose Hill, in the county of Butler and State 5 of Kansas, have invented a new and useful Pad, of which the following is a specification.

The device forming the subject matter of this application is a pad adapted to be used 10 by those who repair motor cars, and other persons, and one object of the invention is to provide novel means whereby scribble strips may be wound up and controlled, novel means being supplied for protecting 15 the strip and for holding against rotation, the shaft whereon the strip is mounted.

It is within the province of the disclosure to improve generally and to enhance the utility of devices of that type to which the 20 invention appertains.

With the above and other objects in view, which will appear as the description proceeds, the invention resides in the combination and arrangement of parts and in the 25 details of construction hereinafter described and claimed, it being understood that, within the scope of what is claimed, changes in the precise embodiment of the invention shown can be made without departing from 30 the spirit of the invention.

In the accompanying drawings:—

Figure 1 shows in front elevation, a device constructed in accordance with the invention, parts being broken; Fig. 2 is a longitudinal section on the line 2—2 of Fig. 1; and Fig. 3 is a perspective showing the shaft and its cap; Fig. 4 is a fragmental perspective disclosing the coöperation between the guide flange and the bearing.

40 In carrying out the invention there is provided a back plate or a body 1 shaped along its longitudinal edges to form overhanging guide flanges 2. Along its upper edge, the body 1 is supplied with spaced tubular bearings 3 having free ends engaged as shown at 4 with the upper ends of the guide flanges 2. A suspending tongue 5 projects upwardly from the upper edge of the body 1, between the bearings 3 and includes a body 45 9 and a neck 10 which is narrower than the body. The tongue 5 is offset rearwardly, as shown at 6, at the point of juncture between the body 9 and the neck 10 to form a trough-shaped socket 8. Further, the body 50 portion 9 of the tongue 5 is offset rearwardly, at the point of juncture between

the tongue and the body, to form a bearing 6. The neck 10 of the tongue 5 is supplied at its upper end with a hook 7. At the upper end of the body 9 of the tongue 5, 60 forwardly and downwardly extended clips 11 are fashioned, the same being located at the ends of the socket 8. A pencil 12 may be inserted into the clips 11 and will be held thereby in the socket 8.

A shaft 14 is journaled for rotation in the bearings 3 and has a slot 15 defining arms 16 which are tapered terminally as indicated at 17 for reception in the opening 18 of a cap 19, which, coacting with one bearing 3, prevents the shaft 14 from moving endwise in one direction, the shaft being terminally provided with an enlarged head 20, which, coöperating with the other bearing 3, prevents the shaft from moving in an 75 opposite direction.

The numeral 21 denotes a strip which may be made of paper or any other suitable substance, the strip being of any length desired. The strip is adapted to slide beneath 80 the guide flanges 2 in contact with the back plate or body 1, the upper end of the strip being received in the slot 15 of the shaft 14, and the arms 16 on the shaft being clamped on the strip when the tapered ends 17 of the 85 arms are thrust into the opening 18 on the cap 19. When the shaft 14 is rotated in the bearings 3 by means of the head 20, the strip 21 will be rolled around the shaft in a way understood clearly when Fig. 2 is 90 noted. The strip 21 may be inscribed as indicated at 22, with data of any kind relating to the business in connection with which the device is used.

The strip 21 may be housed beneath a 95 closure plate 23, made of celluloid or some other flexible transparent material. The closure plate 23 is adapted to be pushed upwardly beneath the guide flanges 2 and is provided with a bottom strip 24. It is to be 100 observed that when the closure plate 23 is pushed upwardly as aforesaid, the upper end of the closure strip is engaged, reflected rearwardly and bent by that portion of the strip 21 which is wound around the shaft 105 14, the upper end of the closure plate being denoted by the numeral 25. This construction and operation results in two functions. First, the closure plate is held in place so that it cannot slip downwardly, and, secondly, the upper end 25 of the closure strip 110 acts as a friction brake which, coöperating

with the rolled portion of the strip 21, prevents an unrolling of the strip or an accidental rotation of the shaft 14.

Having thus described the invention, what is claimed is:—

- 5 1. In a device of the class described, a back plate provided along its longitudinal edges with overhanging guides, the plate being supplied at its upper extremity with tubular bearings having free ends engaged 10 with the upper ends of the guides; a shaft journaled in the bearings; and a scribable strip slidable beneath the guides and assembled with the shaft, the strip passing beneath the free ends of the bearings.
- 15 2. In a device of the class described, a back plate provided along its longitudinal edges with overhanging guides, the plate being supplied at its upper extremity with a tubular bearing; a shaft journaled in the bearing; a scribable strip slidable beneath the guides and assembled with the shaft; and a closure plate mounted in the guides in front of the strip, the upper end of the

plate being engaged with that portion of 25 the strip which is wound about the shaft.

3. In a device of the class described, a back plate provided along its longitudinal edges with overhanging guides, the plate being supplied at its upper extremity with 30 tubular bearings having free ends, that portion of the back plate which lies between the inner ends of the bearings being extended upwardly to form a suspension tongue; a shaft journaled in the bearings, 35 the tongue being rearwardly bulged to form a supplemental bearing coöperating with the shaft; and a scribable strip slidable beneath the guides and assembled with the shaft.

40 In testimony that I claim the foregoing as my own, I have hereto affixed my signature in the presence of two witnesses.

GUS W. REYER.
